UNITED STATES PATENT OFFICE.

HENRY D. JAMES, OF PITTSBURGH, PENNSYLVANIA, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

ELECTRIC-CIRCUIT CONTROLLER.

1,164,001.

Specification of Letters Patent. Patented Dec. 14, 1915.

Application filed May 23, 1908. Serial No. 434,637.

To all whom it may concern:

Be it known that I, HENRY D. JAMES, a citizen of the United States, and a resident of Pittsburgh, in the county of Allegheny and State of Pennsylvania, have invented a new and useful Improvement in Electric-Circuit Controllers, of which the following is a specification.

My invention relates to electric circuit controllers and it has for its object to provide a device of this character that shall be simple and durable in construction and specially adapted for controlling small motors such as are frequently employed for driving textile machinery.

My improved switching device is very compact and may be easily repaired or replaced, and it also differs from the controllers of the prior art in various important particulars.

Figure 1 of the accompanying drawings is an elevation, with the supporting and inclosing parts shown in section on a line I—I of Fig. 2, of a circuit controller constructed in accordance with my invention, and Fig. 2 is a plan view of the controller shown in Fig. 1, the inclosing casing being shown in section on a line II—II of Fig. 1, to disclose the operating parts.

Referring to the drawings, the controller here illustrated has an inclosing casing 1 composed of a top casting 2 and a sheet metal tank 3 and comprises a plurality of stationary terminal members 4, a corresponding number of movable contact fingers 5 and operating crank arms 6 and 7. A supporting base plate 8 is secured to inwardly projecting lugs 9 and 10 of the top casting 2 by means of bolts 11 and the contact-bearing shafts 12 and 13 are supported thereby and project downwardly therefrom.

The upper end 14 of the shaft 12 projects into a hole 15 in the supporting casting 8 and is rigidly secured in position by a dowel pin 16. The major portion of the shaft 12 is substantially square in cross section and is provided with a sleeve 17 of insulating material. The shaft 13 is similarly supported by the casting 8 except that it projects through a hole 18 and is journaled therein, the crank arm 6 being secured to its upper end.

The top wall of the casting 2 is provided with a boss 20 having a hole 21 that is sub-

stantially in alinement with the shaft 13 55 and serves as a bearing for a short shaft 22 that forms a part of the crank arm 7 and is provided with an operating handle 23. The outer end of the crank arm 7 is provided with a downwardly projecting pin 25 60 and the outer end of the crank arm 6 is similarly provided with an upwardly projecting pin 26, the said pins being connected together by a helical spring 27, which holds the crank arm 6 against a stop 19 when the handle 23 is in position *a* in Fig. 2.

A terminal block 28 of insulating material is secured to the base plate 8 above the shaft 12 by means of bolts 29 and is provided with a plurality of terminal binding posts 30. 70 The top casting 2 is provided with an opening directly above the terminal block 28 over which is fitted a detachable cover plate 34 in order that the connecting leads may be readily secured to, or detached from, the 75 terminal posts 30.

Each of the stationary terminal members 4 comprises a member 35 of U-shape which is fitted upon the insulating sleeve 17 and a contact strip 36 which is secured to the ends 80 of the U-shaped member by screws 37. Each U-shaped member 35 is provided with a boss 38 to which a terminal clip 39 is fastened, suitable conductors (not shown) being interposed between said terminal clips 85 and the terminal posts 30. The several stationary terminal members 4 are separated by arc shields or spacing plates 40 which are also secured to the U-shaped members 35.

Each of the movable contact fingers 5 90 comprises a base 41, which is secured to the insulated rod 13 by a clamping screw 31, a rigid arm 42, and a resilient arm 43 having a contact block 44 at its outer end. The resilient arm 43 is secured to the rigid arm 42 95 near the base 41 by an adjusting bolt 45 and movement of the contact block 44 with reference to the outer end of the arm 42 may be limited by a screw 46.

Each clamping screw 31 is provided with 100 a clip 32 from which a conductor (not shown) leads to a corresponding terminal post 30, there being a terminal post for each finger 5 as well as one for each terminal member 4. When it is desired to close the 105 circuit, the handle 23 is moved from position *a* to position *b*, thus placing the spring 27 under greater tension and, at the same

time, swinging it upon the pin 26 as a center until it passes the axis of the shaft 22 when it will quickly move the crank arm 6 away from its stop 19 and thus throw the 5 fingers 5 into engagement with the corresponding contact strips 36, the reverse or opening movement being a similar snap movement.

Blocks 47 project inwardly from the walls 10 of the tank 3 at diametrically opposite points and are provided with bolts 48 to fit into recesses 49 and 50 in the lugs 9 and 10 of the casting 2 and clamp the blocks and lugs together.

15 In service, the controller or switch illustrated is usually secured to a vertical wall or plate by bolts or other suitable means which secure the top casting 2 in position. It is therefore possible to quickly and easily 20 remove the entire switching mechanism by first loosening the bolts 48 and removing the tank 3 and then unscrewing the bolts 11 by which the casting or supporting plate 8 is secured to the lugs 9 and 10.

25 Since the spring 27 is provided with open-hook ends to engage the pins 25 and 26, it will not interfere with the removal of the base plate and the parts supported thereby.

It will be readily understood that, in case 30 of accident to the controller, the operating parts may be quickly and easily replaced by duplicate parts and, since, in textile work, it is desirable to employ a large number of such switches at various points about a machine, the advantages of this arrangement 35 are readily apparent.

It is conceivable that various structural modifications may be effected within the scope of my invention, as defined in the appended claims.

I claim as my invention:

1. In a switching device, the combination with a horizontal base plate and two downwardly projecting shafts, one of which is

rigidly and the other of which is rotatably 45 supported by said base plate and is provided with a crank arm, of a set of contact terminal members secured to the rigidly supported shaft, a set of resilient contact fingers secured to the rotatably supported shaft, an 50 operating handle having a crank arm and a spring connecting the free ends of the crank arms together for imparting a snap movement to the rotatably mounted shaft.

2. In a switching device, the combination 55 with a hollow top casting, a horizontal plate detachably secured thereto, a stationary shaft secured to the plate and projecting downwardly therefrom, and contact terminal members secured to said shaft and insulated therefrom, of a second shaft substantially parallel to the first and having a substantially cylindrical upper end which projects through a hole in the horizontal plate and is journaled therein, a crank arm 65 secured to the upper end of the shaft, contact fingers secured to the shaft below the plate, an operating crank arm rotatably supported by said casting, and resilient means for operatively connecting said crank arms 70 together.

3. A controller comprising a casing, a base plate removably secured to said casing, a set of stationary contact terminal members, and a set of movable contact terminal members 75 supported by said base plate, an operating handle and a crank arm mounted on said casing, a crank arm rigidly connected to said movable contact terminal members, and a spring to the respective ends of which said 80 crank arms are detachably connected.

In testimony whereof, I have hereunto subscribed my name this 16th day of May, 1908.

HENRY D. JAMES.
